US00D964384S

(12) **United States Design Patent** (10) **Patent No.:** **US D964,384 S**
(45) **Date of Patent:** **** Sep. 20, 2022**

(54) **DISPLAY SCREEN OR PORTION THEREOF
WITH A GRAPHICAL USER INTERFACE**

(71) Applicant: **BEIJING KONGMING
TECHNOLOGY CO., LTD.**, Beijing
(CN)

(72) Inventors: **Yunling Feng**, Beijing (CN); **Libin
Chen**, Beijing (CN); **Lu Yu**, Beijing
(CN); **Yue Dong**, Beijing (CN); **Xinyi
Li**, Beijing (CN); **Heli Song**, Beijing
(CN)

(73) Assignee: **BEIJING KONGMING
TECHNOLOGY CO., LTD.**, Beijing
(CN)

(**) Term: **15 Years**

(21) Appl. No.: **29/767,229**

(22) Filed: **Jan. 21, 2021**

(30) **Foreign Application Priority Data**

Jul. 21, 2020 (CN) 202030400053.9

CLAIM

We claim the ornamental design for a display screen or portion thereof with a graphical user interface, as shown and described.

DESCRIPTION

The FIGURE is a front view of a display screen or portion thereof with a graphical user interface showing our new design.

(Continued)

The outermost broken line rectangle illustrates a display screen or portion thereof and forms no part of the claimed design.
